UNITED STATES PATENT OFFICE.

HARRY R. VAN DEVENTER, OF NEW YORK, N. Y.

DIAL FOR INSTRUMENTS.

Application filed June 27, 1923. Serial No. 647,999.

To all whom it may concern:

Be it known that I, HARRY R. VAN DEVENTER, a citizen of the United States, residing at New York city, in the county of 5 New York and State of New York, have invented certain new and useful Improvements in Dials for Instruments, of which the following is a specification.

The present invention relates to dials, and 10 particularly to a combination knob and dial as commonly employed on electrical instruments for manually adjusting the same. Such dials are employed with radio apparatus, particularly radio receiving sets, for 15 adjusting variometers, variable condensers, rheostats and the like.

In radio apparatus and apparatus for other purposes, it is customary to mount devices such as rheostats or condensers in the 20 rear of a panel or mounting plate, through which the shaft of the device projects. On the outer end of the shaft is placed the combination knob and dial for the purpose of adjusting the device, and indicating by 25 means of suitable graduations on the dial or adjacent thereto, the adjusted position of the device.

It is obvious that in some cases the dial device must rotate from left to right, while 30 in others it is necessary that the rotation be from right to left. This has in the past necessitated the manufacture of dials reading both right and left-handed, which means that a dealer must carry in stock many more 35 dials than would be necessary if a single dial would serve for devices rotating in either direction.

Another difficulty heretofore met with has 40 been to properly secure the knob and dial to the shaft of the device. When set screws or the like are used for this purpose, the results are unsatisfactory, the screws causing burrs on the shaft which make adjustment difficult, besides causing the knobs 45 (usually made of molded material) to split unless provided with metallic inserts which are an added expense.

This invention has for its object the provision of a dial adapted for either right or 50 left-handed rotation.

Another object of the invention is to provide means for clamping the dial and knob upon a shaft.

Another object is to provide a dial in 55 which the metal parts thereof act as a static shield when the dial is used with electrical

condensers or the like, and a still further object is to provide a combination knob and dial in which the attaching screw may be completely surrounded by insulating material so that it cannot be touched by the hand, when the knob is grasped. 60

A further object is to provide apparatus having a knob, with a separable front forming a name plate, and a dial also having a 65 separable front which, by being reversed, adapts the indicia thereon for either right or left-hand rotation of the apparatus.

In the accompanying drawings,

Figure 1 is a front view of a combination 70 knob and dial complete except the screw cover or name plate, and arranged for left-hand rotation;

Figure 2 is the same dial as in Figure 1 except arranged for right-hand rotation; 75

Figure 3 is a sectional view of the dial of Figure 1, with the screw cover or name plate in place;

Figure 4 is a bottom view of the dial of 80 Figure 1;

Figure 5 is a front view of the dial of Figure 2 with a modified form of screw cover in place;

Figure 6 is a sectional view of the dial of 85 Figure 5 and also shows a slightly different form of clamping device from that shown in Figure 3;

Figure 7 is a bottom view of the dial of Figure 5 showing a modified form of clamping device, and 90

Figure 8 is a view, partly in section, showing the clamping device in Figure 7.

Referring to Figure 1, the numeral 1 denotes a circular conically-flanged disc-like member preferably made of metal. Upon 95 the sloping surface 2 of this member suitable graduations or other indicia as shown in the figures may be embossed or marked in any suitable manner. The member 1 is further provided with a circular depression in which is placed the separable front or number disc 3. This disc is provided on one side with a set of numerals or other indicia as indicated by the numeral 4. Assuming this to be the "left-hand" side of the disc, 100 the numbers would read from left to right, as shown in Figure 1. On the back of the disc, the numbers would read from right to left as indicated by the numeral 5, Figure 2, thus adapting the disc for "right-hand" 110 rotation. Members 1 and 3 may be said to comprise a dial having a separable front.

It will now be observed that by placing disc 3 on top of the member 1 that a dial is provided having graduations on its outer edge and with numerals or other indicia reading either right or left-handed, as desired.

The members 1 and 3 being placed upon each other as described, a knob 6 of suitable insulating material is placed with its central boss 7 projecting through the central apertures provided in members 1 and 3, and the locking screw 8 is placed through a hole in the knob as shown, and engages the locking member 9.

15 The complete assembly may now be placed upon the shaft 10 and secured thereto by tightening screw 8. This pulls the locking member 9 sideways upon the shaft, which is tightly gripped. The screw 8 holds the 20 assembly consisting of knob 6 and the members 1 and 3 together, or if desired, auxiliary screws 11 and 12 may be used to attach the members 1 and 3 to the knob 6 independently of the screw 8.

25 The locking member 9 is raised sufficiently from the lower surface of the member 1 to prevent pulling the knob and dial assembly sideways by providing some means, such as the projection 13 which will raise the 30 outer or free end of the locking member 9 so that the said member, when in its tightened position, will tightly grip the shaft 10 at substantially right angles thereto.

35 After the knob and dial have been attached to the shaft 10, it is desirable to close the opening 14 in the end of the knob. This is accomplished by providing the screw cover or name plate 15 which may be of metal, celluloid, or any other suitable material, and which is simply pressed into the depression 14 in the knob, as shown in Figure 3. The name plate 15 may be reversible. The knob 6 and plate 15 may be said to comprise a knob having a separable front.

40 An alternate arrangement is shown in Figures 5 and 6 in which the screw cover 15 consists of a flat piece of material held in position by means of the spring ring 16. I consider these methods of covering the 45 screw 8 of importance for it prevents the possibility of the hand making contact with the screw 8, which is undesirable, and also, the screw covers may form the name plate and being arranged in the manner shown, a 50 ready means of changing the name plates is provided which is of extreme importance to a manufacturer supplying a large number of concerns, each of whom desires the dials with their own name plate. Heretofore it 55 has been necessary to furnish a separate and complete dial for each customer or make up some part of the dial special in each case, whereas with the arrangement shown, the 60 customer's name plate formed by the member 15 may be put on the dial at any time.

In Figure 6 I have shown a modified form of locking member which is indicated by the numeral 17. This form of locking member bears against the downwardly projecting portion 8 of member 1, and eliminates the necessity of forming the extra projection 13, Figure 4, and for some diameters of shaft, Figure 6 is the preferred arrangement.

70 Figures 7 and 8 show a further modification in respect to the locking member which is provided with a slot 19 in which is positioned the screw 20, which serves to position the locking member in relation to the shaft. By providing the screw 20 as well as 75 the screw 8, the knob 6 may be very securely attached to the dial members 1 and 3 which in the case of large and heavy dials and knobs is preferable.

I claim:

- 85 1. Apparatus embodying a knob having a separable front and a dial having a separable front supported by said dial connected to said knob and supported thereby.
2. Apparatus embodying a knob and a dial having a separable front, and means securing said knob and dial together.
- 90 3. Apparatus embodying a knob, a dial supported thereby and having a separable front with indicia on both sides thereof.
- 95 4. Apparatus embodying a knob, a dial member secured thereto and having indicia marked thereon, and a disc adapted to overlie said dial member having indicia on both sides thereof whereby said apparatus may be 100 adapted to indicate either right or left-hand rotation.
5. Apparatus embodying a knob and a circular disc-like member forming a dial having indicia thereon supported by said 105 knob a reversible disc adapted to overlie said dial and provided with indicia adapted to cooperate with said first mentioned indicia for the purpose set forth.
- 110 6. In combination, a shaft, a knob, means for securing the knob to the shaft and a reversible name plate mounted upon said knob and concealing said securing means.
- 115 7. In combination, a shaft, a knob and dial mounted thereon and means adapted to secure said knob and dial together in relative position and attach them to said shaft.
- 120 8. In combination, a shaft, a dial carried thereby, a knob mounted upon said shaft, means carried by said dial for changing the indicia thereon, and common means for securing all of the foregoing parts to said shaft.
- 125 9. In combination, a shaft, a knob mounted thereon, a dial having indicia thereon and secured to said knob, means for changing said indicia to read in either direction, and means for securing said knob and dial to said shaft.
- 130 10. In combination, a shaft, a knob mount-

ed thereon, a dial having indicia thereon secured to said knob, means for changing said indicia to read in either direction, means passing through said knob for securing same to said shaft, and a removable plate carried by said knob and covering said securing means.

11. In combination, a shaft, a knob mounted thereon, a dial adapted to move with said knob, an apertured member on said shaft

and a screw passing through said knob and dial and engaging said member whereby all of said parts are secured to said shaft, substantially as described.

12. A combination knob and dial for instruments embodying a part adapted to be reversed for the purpose of indicating rotation in either direction.

In testimony whereof I affix my signature.

HARRY R. VAN DEVENTER..
